Specification of Letters Patent.

Patented Sept. 7, 1915.

Application filed March 30, 1912. Serial No. 687,434.

To all whom it may concern:

Be it known that we, GEORGE P. CLARK, WILLIAM F. IRRGANG, and GEORGE E. CLARK, citizens of the United States of America, residing at Windsor Locks, in the county of Hartford and State of Connecticut, have invented new and useful Improvements in Trucks, of which the following is a specification.

- 10 This invention relates to that class of transporting trucks in which some means is provided for elevating the platform or frame on which the load is to be transported. The usual method of handling these trucks is to roll the truck under a platform bearing the load, then elevating the platform, or frame, of the truck until it lifts and supports the platform holding the load. When this has been done the truck 15 can transport the load as a unit and unload it as a unit in a similar manner. In other words, with this class of trucks it is unnecessary to load and unload material by hand. It has been found with trucks heretofore 20 used that heavy loads required the operator to be exceptionally strong, heavy or skilful. The object of this invention is to provide a truck of the class described which does not require an operator of skill, weight or 25 strength, but can be operated conveniently by any ordinary workman.

Other objects of the invention will appear in the detailed description and annexed claims.

- 30 In the drawings: Figure 1 is a side view of the truck in position to elevate a platform. Fig. 2 is a perspective view of a portion of the elevating mechanism. Fig. 3 is a side view partly in section of the truck 35 showing the elevating mechanism in position to elevate the platform. Fig. 4 is a similar view with the same mechanism in place to permit the platform to take its lower position. Fig. 5 is a plan view of the 40 mechanism shown in Fig. 2, with certain parts omitted. Fig. 6 is a section taken on line 6—6 of Fig. 5. Fig. 7 is a side view of the truck ready for use. Fig. 8 is a view of the platform with which the truck is used, 45 showing in section the leaf springs controlling the position of the supporting legs. Fig. 9 is a partial sectional view of the supporting leg and its mounting with relation to the controlling springs. Fig. 10 is a sec- 50 tion taken on line 10—10 of Fig. 4. Fig. 11 is a section taken on line 11—11 of Fig. 3.
- The general operation of the truck is as follows: If a load of any kind to be transported is on the platform 3 (Fig. 1), or if it is desired to transport the platform without a load, the truck is rolled under said platform; the handle *t* (see Fig. 7) is swung back until the pin *u* snaps into the hook in bar *n*. The handle *t* is then reciprocated back and forth, operating bar *n*, which in turn operates mechanism to rotate shafts *w* in the frame of the truck. Cams 19, one on each end of each shaft, are turned with said shafts and these cams, operating on rollers 20 of the frame platform *y*, elevate the latter until it bears against and lifts the platform 3. The handle *t* is then unhooked from bar *n* and the truck, with platform 3 thereon, is wheeled to the desired point. If handle *t* is then hooked again into bar *n* and worked back and forth the mechanism which before operated to elevate the truck will, by having the relation of its parts changed by other mechanism, allow the truck to take its lowermost position and allow the legs 1 and 4 of platform 3 to support the latter on the floor, after which the truck is wheeled away to handle another load, leaving the platform 3 at the point desired.
- The specific operation will now be described: Referring to Figs. 2, 3 and 4, the pin *u*, when hooked in bar *n*, pulls the latter back and forth as the handle *t* is rocked. The latter is pivoted on the supporting part *r* and as a result the operator has considerable leverage to move bar *n*. This bar is connected to a rocking member 27, which in turn swings or rocks on supporting pin *z* in the fixed frame 15 of the truck. To the member 27 are hinged the two operating pawls *d* and *e*, one above pin *z* and one below, at points *j* and *k*, respectively. About midway of each pawl a reversing pawl is hinged. These reversing pawls, *f* and *i*, are seen in normal position in Fig. 3. The outer end of pawl *i* bears against a lip *h* of the fixed frame, while the outer end of pawl *f* bears against the outer end of pawl *i*. The normal position of pawls *d* and *e* is shown in Fig. 3, where the outer ends of the pawls are both shown engaging the rack *b*; mov- 55 60 65 70 75 80 85 90 95 100 105 ably mounted in the frame. This rack

meshes with gears g , one on each shaft w , so that these shafts and the cams 19 thereon are turned with the gears. As the bar n (see Fig. 3) is moved back and forth the rocking movement of member 27 operates pawls d and e as follows: On the forward movement of bar n pawl e , pivoted below point l , drives the rack forward one tooth, while pawl d , pivoted above l , snaps back one tooth on the rack and acts as a holding pawl therefor. Then as the bar is forced backwardly pawls d and e reverse operations in an obvious manner, the pawl d operating as the driving pawl and pawl e snapping back one tooth to operate as the holding pawl. During these driving movements the reverse pawls move with the operating pawls and act as a supporting means therefor, whereby said operating pawls are kept in engagement with the rack. Referring to Figs. 5 and 6, each of the reversing pawls f and i have a lug thereon, to which one end of a spring is fastened. Each spring is wound around the pivot pin of the reversing pawl and connected to the corresponding operating pawl, giving this pawl a tendency to always remain in operative position to the rack. When the handle t has been operated long enough to move the rack sufficiently for the cams 19 to raise the truck platform y as far as desired, the operator puts his foot on the ear 30 on bar n and forces n downwardly against spring o . The pin u is thus disengaged from bar n and the handle t can then be used to transport the truck to the desired point. When it is desired to lower the truck platform y after it has been elevated, the operator again forces pin u against bar n (see Fig. 4), depressing said bar until spring o snaps the end hook thereof into engagement with pin u . The back and forth movement of bar n drives the rack b forwardly until the lug 12 thereon contacts with ear 14 of the reversing lever c (see Figs. 2 and 4). The lever c is rocked on its pivot point p and bears down on one or the other of the reversing pawls f and i , accordingly as one or the other is placed in position by bar n to be depressed. An examination of Fig. 2 shows that if bar n is in its back position only the reversing pawl i has one end in position to be forced downwardly when lever c is rocked as described. If bar n is in the forward position then only pawl f will be in position to be depressed. Fig. 4 shows the parts in position for pawl i to be depressed and since the forward end of this pawl is supported by lip h the depression of the back end causes the reversing pawl to act as a lever to force the driving pawl e away from the rack b . The weight of the truck platform bearing against the cams 19 turns shafts w and gears g to force rack b backwardly. As only pawl d is in contact with the rack this backward movement of

the rack will force member 27 to rock counter clockwise and move bar n forwardly. At the same time that pawl d is moved backwardly by the rack its reversing pawl f is forced into contact with lever c and forced downwardly, thus pulling pawl d out of contact with the rack in a similar manner to the withdrawal of pawl e , already described.

The movements of the parts just described will carry the reversing pawl i out of contact with lever c and force pawl e into contact with the rack. The continued backward movement of the rack will force pawl e out of contact and pawl d into contact with said rack in a similar manner to that already described. As lug 12 is removed from contact with ear 14 on lever c the latter is held in reversing position by arm a , pivoted thereto and having a slot 85 therein to receive pin 21 (see Fig. 4). The arm a normally rides on the pin 21 . Whenever the arm is moved for the slot to engage the pin (the spring 31 insures this engagement), the lever c is held in reversing position until arm a is raised to disengage the slot from the pin and force lever c to normal inoperative position. When lever c is in reversing position the pawls d and e , as described, will permit the weight of the truck platform to force the rack backwardly step by step, during which time the platform is lowered. A pin 7 on the end of the rack (see Figs. 2 and 4) is adapted to engage a cam 8 on the arm a to push said arm upwardly and backwardly to restore lever c to normal position. A right angle bend 9 on arm a is positioned at the front of the truck, so that the operator can by hand operate the reversing lever c into either of its 100 two positions. This lever c is thus operated either automatically or manually.

With the truck and its operating mechanism arranged as described, it is clear that it can be used for all the purposes of an elevating truck. The mechanism provided permits a light and weak man to get a sufficient leverage to raise a heavy load on the truck platform, which he would be wholly unable to do were this leverage not possible. The mechanism is as convenient and operated in as simple a manner as many ordinary lifting jacks. The lifting mechanism in this apparatus is, in essential parts, a form of jack.

In Figs. 8 and 9 the platform which is particularly adapted for use with elevating trucks is shown. Each leg is pivoted at one corner of the platform and has a lug 18 bearing against two leaf springs, 16 and 17. The horizontal bearing surface of each leg, when supporting the platform, is on one side of the pivot point and lug 18, arranged at an angle thereto, on the other. After the platform has been loaded on a truck or when it is desired to nest the plat- 120 125 130

forms (a number of which are supplied to each truck), the legs are folded up under the platform and the lug 18 passes across center. The springs 16 and 17 bear against the lug 18 to hold the leg into either its supporting or non-supporting position. As a leg is changed from one position to another the two springs 16 and 17 slide, one relatively to the other. With this arrangement a strong spring action is obtained without danger of snapping the spring as the lug passes across center, as would be the case where a single leaf spring is used.

We claim:

- 15 1. The combination in an elevating truck, of a wheel supported frame, a steering handle, a platform on said frame arranged to be raised and lowered, a rack, a plurality of lifting devices operable therefrom and arranged to move said platform and means to operate said rack backwardly or forwardly in a step by step manner, said means comprising a pair of pawls, a lever, and an operating bar connected to said lever automatically engageable with said handle, said pawls arranged alternately to move said rack in a step by step manner as said handle is moved.
- 20 2. An elevating truck, a handle, a frame, a supporting part mounted thereon arranged to be raised and lowered, a rack slideable in said frame, shafts operable from said rack, cams on said shafts arranged to elevate said supporting part, operating pawls for said rack, a lever arranged to operate said pawls and a connection between said lever and said handle, all constructed and arranged so that said supporting part may be raised or lowered in a step by step manner from said handle.
- 25 3. In a device of the class described a truck frame, a truck platform adapted to be raised and lowered, two shafts mounted in the frame, a cam on each end of each

shaft bearing against the platform, a gear 4^f on each shaft, a rack meshing with each gear, together with two operating pawls, a lever mechanism on which the pawls are mounted, means to operate said lever mechanism, to operate the pawls one after the other, as described.

4. The combination in an elevating truck of a wheel supported frame, a member thereon arranged to be raised and lowered, a handle, a plurality of shafts mounted in 5⁵ said frame, cams on each of said shafts arranged to engage said member, a rack, connections operable therefrom to drive each of said shafts, and means to move said rack backwardly or forwardly in a step by step 6⁰ manner to operate said cams to raise said member, said means comprising a pair of pawls, a lever arranged to move said pawls in opposite directions, and a link connected to said lever and automatically engageable 6⁵ with said handle.

5. The combination in an elevating truck of a wheel supported frame, a handle for hauling and steering said frame, a platform on said frame arranged to be raised and 7⁰ lowered, a rack slideable in said frame, a plurality of cam devices operable from said rack and arranged to move said platform and means to move said rack backwardly or forwardly in a step by step manner, said 7⁵ means comprising a lever, a link connection therewith automatically engageable with said handle and two pawls carried by said lever arranged to move in opposite directions, whereby said pawls alternately act on 8⁰ said rack to move the latter step by step as said handle is moved.
